SPINDLE

Herbert G. Beede and Frederic N. Beede,
Pawtucket, R. I.

Application August 25, 1939, Serial No. 291,970

19 Claims. (Cl. 308—228)

The present invention relates to spindles, and particularly mountings or journals for spindles of spinning and twisting machines. This application is a continuation in part of our joint application for "Spindles and mountings or journals therefor," S. N. 114,997, filed December 9, 1937.

Patent No. 1,511,257, issued to Herbert G. Beede, one of the joint inventors herein, on October 14, 1924 shows the blade of the spindle driven by the usual driving band, and the blade so mounted as to obtain a cushioned lateral movement of the lower portion thereof, to permit alignment or centering of the center of gravity with the axis of rotation of the spindle blade. Spindles and mountings therefor made in accordance with said patent have been used successfully for bobbins of relatively small sizes such as had been in general use for many years. Extensive efforts have been made in recent years to meet the demand or requirements for spindles to attain the desired result of carrying bobbins of greater increase in size, especially as to length of traverse, and with increase in R. P. M.

With the foregoing in mind the general object of the present invention may be stated generally to reside in the provision of a spindle and mounting or bearing therefor capable of carrying a very large bobbin at greatly increased speed and at ordinary speed with true vertical alignment or centering of the center of gravity of the axis of the spindle blade with a bobbin mounted thereon, so as to prevent a hammering effect between the bobbin and the blade as well as between the blade and the mounting or journals.

In actual practice we have found that the object above stated can be and is accomplished by providing a mounting or journal capable of absorbing substantially all vibrations, which vibrations vary with the speed of rotation and the unbalancing of the rotating spindle blade with balanced or unbalanced loaded bobbin. In other words the varying conditions to which the spindle blade is subjected, either because of varying speeds or varying load, or both, result in the creation of a series of vibrations, (primary, secondary, tertiary) which must be substantially absorbed to obtain a smoothly operating spindle.

The ever increasing load or weight on the bobbins, especially at high speed and with large bobbins, causes a gyratory or oscillating action which naturally results in hammering of the bobbins on the blades as well as on the journals which results in destruction of one or more of the parts in a relatively short time, when the proper cushioning is lacking. The spindle and mountings

therefor shown and described in the accompanying drawings, under actual tests has been found to function perfectly over a long period of time and to meet all of the conditions mentioned above. The reasons will be hereinafter pointed out in detail.

A further object of our invention is to eliminate the pumping or splashing of oil which has occurred in former types of bolsters. We have found that if the upper portions of the respective bolster means are so closely spaced at a proper clearance distance from each other or from the bolster case for a substantial distance adjacent the upper end thereof that a continuous film of lubricant will be urged upwards by the vibration of the spindle blade to continuously ooze inwardly over the upper end of the respective bolster means to lubricate the bearing and spindle blade, and thus by selecting the proper clearance between the respective upper ends of the bolster means and outer bolster means and bolster case we are able to substantially eliminate all objectionable forms of splashing present in other types of spindles.

23 We have also discovered that if the respective bolster means are so closely spaced from each other and the outermost bolster means from the bolster case substantially throughout the height thereof, that a continuous upward flow of lubricant will be urged upwardly by the capillary action of the lubricant itself without any rotation of the spindle blade, but that a capillary film will form adjacent the upper end of the bolster case. We have supplementally discovered, however, that the surface tension of this film may be broken by the high speed rotation of the spindle blade thereby permitting the oil to be forced to continuously ooze inwardly over the upper ends of the respective bolster means and downwardly 30 to the lower bearing hole to lubricate the bearings and spindle. Thus by establishing the proper clearance, this continuous upward circulation of lubricant will be provided on rotation of the spindle blade.

45 Before proceeding with a detailed description of the embodiments of the invention illustrated in the accompanying drawings, we would point that the invention applies not only to spindles and mountings therefor embodying antifriction bearings of the type disclosed in the said Patent #1,511,257 in which the bearing is near the pivot of oscillation, but to spindles and mountings of the plain bearing type, as well as spindles and mountings using antifriction bearings regardless

of the exact location of the antifriction bearing relative to the whirl.

In the accompanying drawings:

Fig. 1 is an elevation of a spindle and mounting embodying the present invention with a large bobbin thereon;

Fig. 2 is an enlarged vertical sectional view taken on the line 2—2 of Fig. 1, with a portion of the bobbin and parts surrounding the blade broken away;

Fig. 3 is a view similar to Fig. 2 showing modification of the invention; and

Figs. 4 and 5 are views similar to Figs. 2 and 3 showing further modifications of the invention.

Fig. 6 is an enlarged vertical sectional view similar to Fig. 2 showing a modification of the invention with the plug removed to permit initial axial flow out the lower end of the bearing hole prior to its radial circulation outwards.

Fig. 7 is a cross sectional view taken along the line 7—7 of Fig. 6.

Fig. 8 is a cross sectional view taken along the line 8—8 of Fig. 6.

Fig. 9 is a cross sectional view taken along the line 9—9 of Fig. 6.

In the drawings, the letter B designates generally the bobbin having end flanges, 6, between which the thread is spun or twisted during a relatively long traverse. The illustrated bobbin, as previously mentioned, is of sufficient size to contain at least a pound of thread, or yarn. The numeral 7 designates generally a bolster-case adapted to be secured to the usual rail R by means of the lock nut 8 to hold the bolster-case securely in proper position. A bolster 9, extends substantially to the top of the bolster case 7 and is loosely fitted in the bolster-case so as to have a floating action. A ball bearing, 10, is shown arranged within the upper end of the bolster, 9. Blade 11, of the spindle is keyed or fastened to the inner race of the ball bearing, and is driven by the whirl 12, which also receives and drives the bobbin, B.

The lower end of the blade 11, is pointed as indicated by the numeral 13, and rests on the surface 14, of a wear resisting plug 15, held within the step 16, by pin 17, which also connects step 16, to the inner bolster 18. The lower end of the blade 11 is loosely contained within a central hole 15a within the step 16. Thus the load is supported by the inner bolster 18, and relative rotation between the bolsters, 9 and 18, is prevented by pin or key 19, located adjacent the top of the inner bolster 18. It will be noted that the inner bolster extends a substantial distance upwardly within the outer bolster 9, and is arranged concentrically therewith and in slight spaced relation thereto. The purpose of these constructions will be presently pointed out in connection with the operation of the spindle.

Since the inner bolster 18 carries step 16 receiving the reduced lower end of blade 11, and plug 15, which forms the bearing for the lower end of the blade 11, and is loosely fitted within bolster 9, several relative movements are possible to absorb all vibrations. For instance, the bolster 18 may move laterally relative to the bolster 9, the bolster 9 relative to casing 7, and blade 11 relative to bolster 18. It should be noted that the pin 19, is arranged within a relatively large opening 20 facilitating relative movements between the bolsters.

In the construction of Fig. 2, as shown and described, the load is supported on the lower end of the blade and by bolster 18, but the spindle

may be supported on the ball bearing as in the case of the said Patent # 1,511,257, without departing from the essential and novel features of the present invention.

As previously mentioned the inner bolster 18 is loosely mounted within the bolster 9, which is also loosely mounted within the case 7. Thus oil or other lubricant supplied to the interior of the case forms films between the case and bolster 9, as well as between the bolster 18 and bolster 9, and around the lower portion of blade 11. In order for an oil film to be formed between the case 7 and the outer bolster 9 capable of being continuously urged upwards by the rotation of the spindle blade, the outer bolster 9 must be closely spaced from the bolster case for a substantial distance adjacent the upper end thereof. The exact clearance distance depends somewhat on the nature and viscosity of the lubricant employed. With standard types of light lubricating oil, a radial clearance of about .002 inch has been sufficient to provide the creation of a continuous upwardly traveling oil film between the outer bolster 9 and case 7 on rotation of the spindle blade. In the prior art this result has not been attained for this clearance has been much greater, size for size of spindle blade. On the other hand, the clearance must not be too small to prevent the formation of oil globules to make up the film. With the proper clearance between the outer bolster 9 and the bolster case 7 for a substantial distance adjacent the upper end thereof, on the rotation of the spindle blade a continuous film of lubricant will be urged upwardly by the rotation and vibration of the spindle blade aided by the capillary action and surface tension of the lubricant. We believe we are the first to provide a structure in which both the vibration and rotation of the spindle blade and the capillary action and surface tension of the lubricant will cause a continuous film of lubricant to be urged upwardly between the outer bolster 9 and bolster case 7 to form a continuous radial cushion for the radial upper ball bearing 10 and to continuously ooze inwardly over the upper end of said outer bolster 9 and downwardly within said bolsters to lubricate said bearing and spindle blade. When the clearance is too great, however, the upward travel of the oil, which is common to all spindles, is so violently hammered in intermittent spouts that it is carried over the bolster case 9. Prior to our invention, it has been impossible to make a single bolster which will accomplish this result as larger clearances are required to cushion the oscillatory movements of the lower end of the spindle blade. Employing our invention, however, the outer bolster is spaced from the bolster case the above amounts to insure the feeding of a continuous film of lubricant upwardly therethrough and the required clearances for providing oil cushions of sufficient areas are provided between the bolsters themselves to absorb substantially all of the oscillatory high speed vibrations of said spindle blade, thus with a typical load we have provided a .010 inch clearance between the outer bolster 9 and the inner bolster 18 in the medium size textile spindle shown. While this may in the construction shown in Fig. 2 provide intermittent spouts of lubricant between the upper end of the inner bolster 18 and the outer bolster 9, these do no harm as they are immediately deflected downwardly by the ball bearing 10 and aid in lubricating the radial thrust ball bearing and spindle. We preferably, however, design the

spindle in every case possible to have the same clearance between the inner bolster and outer bolster as to also feed a continuous film of oil upwardly between the inner bolster and outer bolster to continuously ooze inwardly over the upper end of the inner bolster, or bolsters, and downwardly thereof into the oil reservoir located centrally thereof around the lower end of the spindle blade. As stated hitherto, our improved construction permits of high speed rotation of a flexibly cushioned vertically mounted type of spindle blade carrying proportionately heavy unbalanced loads from 6,000 R. P. M. up to 20,000 R. P. M., a feature not possible in any known type of such spindle. It has been found in practice in the prior art that such a medium size textile spindle suitable for approximately three pound bobbins reaches a maximum limit, normally between 6,500 to 7,000 R. P. M., often called the critical speed in the trade to which it may be driven and prior to our invention no such a spindle has been provided capable of being driven at a greater speed than said critical unless with a perfectly balanced bobbin. Apparently at around this critical R. P. M. a substantial shift in the position of the axis of rotation of the rotating spindle blade and bobbin takes place and prior art structures have been incapable of accomplishing this shift. Employing our invention, however, it is possible to observe the shift at the axis of rotation as the rotating spindle blade increases in speed which shift, however, is hardly noticeable and in no manner interferes with the operation of the spindle. This shift is usually accompanied with a slight noise and a gyroscopic movement of the spindle blade. In attempting to force prior art spindle blades through this so-called critical R. P. M., the entire spindle blade vibrates excessively accompanied by much noise, and it has been almost impossible to drive them through the critical speed to the higher speeds desired. We have observed, however, that even if the spindle blade is stationary, if a proper clearance is provided between the respective inner and outer bolsters and the outer bolster and case throughout the height thereof, thin annular bodies of lubricant will rise respectively in said respective places substantially to the tops of the respective bolsters by the capillary action and surface tension of the oil alone but the surface tension is so great that the films will not ooze inwardly over the respective upper ends of the bolsters. If, however, the spindle blade be suitably rotated, this surface tension will be broken to permit a continuous circulation of lubricant radially inwardly over the tops of the respective bolsters, and we therefore, preferably provide such a respective clearance between the respective bolster means and outer bolster and bolster case throughout the height thereof for the more ready circulation of oil in the manner explained, and we have found by experience that if these clearances be maintained, that cushioning bodies of lubricant will be provided of substantial thickness to cushion the aforementioned sets of vibration. These films are formed and circulation of the lubricant is effected during the rapid rotation, ten to fifteen thousand revolutions per minute, and by a capillary action between the bolsters urged on by the fine vibration of the high speed which causes the lubricant to travel upward around the outside very slowly and to flow down through the center of the spindle around the blade, to within the hole 15^a to also form a cushioning

oil film 16^a between the wall of said hole and the lower end of said spindle blade. Suitable oil holes 9^a and 18^a are formed respectively in the respective bolsters 9 and 18 to carry oil from said oil film 16^a formed in the hole 15^a radially outwards through said bolsters so that the respective oil films may be fed upwards as aforesaid between the outer bolster and case by said aforesaid capillary action between the bolsters, urged on by the fine vibration and high speed oscillation of the spindle blade which causes the lubricant to travel upwards very slowly between the bolster means and the outer bolster means and case to ooze radially over the respective tops of the bolster means and to flow down through the center of the spindle around the blade into the reservoir 16^a formed in said step 15^b between the lower end of the spindle blade 11 and wall of said step bearing hole 15^a. The primary vibration is set up by the blade. This primary vibration is accompanied by secondary and tertiary vibrations which must be cushioned to prevent hammering of the spindle and distortion of the blade to provide for smooth and even rotation especially where a heavy load is carried at the top of the blade under the very rapid rotation above mentioned. Thus in general the primary vibrations in a spindle are those caused by faults in the spindle itself including the blade and whirl and are absorbed by the looseness of the blade set in the step bearing in the expansible oil film surrounding the blade at this point; the secondary vibrations are caused by faulty bobbins and poor fit of bobbin on spindle blade, which quite often give a different set of vibrations, often in different frequency or non-harmonic with the primary vibrations and the tertiary vibrations may be classed as those caused by mis-alignments due to uneven and faulty loading of the bobbin, which usually are of a different frequency and non-harmonic with the primary and secondary vibrations.

However, it usually happens with a large loaded bobbin that at least three different sets of harmonic or non-harmonic vibrations of different frequency are usually present during the rotation of the spindle blade. As stated, the primary set of vibrations may be absorbed between the blade and step bearing, the secondary set between the inner and outer bolsters and the third or tertiary set of such vibrations may be absorbed between the outer bolster and bolster casing.

If a larger plurality of different sets of vibrations be produced, it is obvious that successive sets of oil films to cushion these different sets of vibrations may be provided by providing a greater plurality of closely nested, variably separable or spaceable bolsters.

In actual practice, we have found that spindles constructed in accordance with the present invention successfully operate for long periods of time under the condition mentioned, because the several vibrations are cushioned and adequately taken care of by the relative movements between the blade, inner and outer bolsters and between the outer bolster and case. It is essential to provide for cushioning the increased load on a large bobbin to deaden gyroscopic action, and the provision of means to cushion the vibrations is an essential feature in this connection. When these types of vibrations, which vary according to the load and speed of rotation, are absorbed around the lower portion of the spindle the gyroscopic or oscillating action of the bobbin is cushioned and

smooth and quiet operation with long life to the spindle and bobbin is provided.

Fig. 3 shows a modification of the invention in which the casing 7' is provided in its lower end with seat 22, for the outer bolster 23, loosely mounted within the casing 7', and provided at its upper end with an enlarged head 24. The head 24 has a shoulder 25 confronting the annular ledge 26 within the casing 7'. The head 24 is provided with an annular groove 27, and also carries a key 28, which fits in longitudinal groove 29 of the casing to prevent relative rotation between the bolster 23 and the casing. The head 24 of bolster 23, is also provided with a groove 30, which receives key 31 of the inner bolster 32 to prevent relative rotation between the respective bolsters. The upper end of the bolster 32, is also provided with a head 33, having an annular groove 43, substantially in alignment with the groove 27 when the parts are completely assembled.

In the embodiment of the invention being described the movable bolsters are supported by their shoulders or bases.

Blade 35, is driven by usual whirl 36, and the inner surface of the head 33, of the bolster 32, forms a journal for the portion 38, of the blade. The lower part of the blade 35, tapers gradually inwardly and downwardly within the bolster 32, providing a gradually increasing space 39, between the bolster 32 and the blade 35. The lower pointed end 40 of the blade 35 is shown seated on a bearing surface 41 of the bolster 32. The lower end of the bolster 32 is pivotally supported on seat 42 of bolster 23. The bolster 23 is separated from the casing 7' by tapering space 43, and the bolster 32 is similarly spaced from the bolster 23, as indicated at 44. This provides for relative movements between the respective bolsters and between the bolster 43 and casing 7' for the purpose of balancing the load on the upper end of the blade 35 as explained in connection with Fig. 2, by absorption of the vibrations created during the rotation of the bobbin and the building-up of the load thereon.

The lubricant is fed through passage 45 to the opening 46 in bolster 23 to space 44 between the bolsters. The bolster 32 has an opening 47, to supply lubricant to the bearing 41, and the lower end of the bolster 23 has an opening 48 to supply the lubricant to the space 43. The lubricant openings may be varied in number and relative location as desired.

When the lubricant circulates throughout the inner structure in the manner previously described, that is by upward flow between the respective inner and outer bolsters and outer bolster and bolster case, inward radial flow over the respective tops of the bolsters and downward flow, over the upper bearing and spindle blade into the well 16^a and radial outward flow through the respective passages 47 and 48 to the respective spaces between the inner and outer bolsters and outer bolster case, the spaces between the relatively movable parts are filled with bodies of lubricant which cushion the parts to absorb the vibrations, (primary, secondary and tertiary), providing smooth operation, and preventing hammering between the blades and bobbins even when the weight of the thread spun or wound on the bobbins is relatively large and varies throughout the spinning operation.

Fig. 4 shows a further modification of the invention which, however, embodies the essential general principles before mentioned and de-

scribed. In Fig. 4 the numeral 50 designates the casing within which are mounted the bolsters and blade. Bolster 51 is shown seated on its lower end on the seat 52 of the casing 50, and arranged loosely within the casing for lateral movements relative thereto. Whereas, in the embodiments of the invention hereinbefore described the outer bolster, extended substantially to the upper end of the casing, in the present embodiment of the invention the upper end of the bolster 51 terminates substantially in alignment with the rail on which the spindle is mounted, as designated by the numeral 53. The inner bolster 54 is provided with a step or bearing 55, which supports the lower end 56 of the blade 57. The lower end of the inner bolster 54 rests on a seat 58 at the bottom of bolster 51; the arrangement being generally similar to that provided for the corresponding parts in Fig. 3.

The inner bolster 54 extends above the outer bolster in the construction of Fig. 4, and is provided with an enlarged head or end 59, which is located in a chamber 60, defined by the walls 61 on the upper end of the casing or support 50. The head 59 is provided with a chamber 62 in which is mounted a ball bearing 63 as shown also in Fig. 2.

As in the other embodiments of the invention the blade designated by numeral 57 is rotated by whirl 64. The head 59 of the inner bolster is provided with an annular groove 65, to facilitate lubrication. Key 66 engages a longitudinal groove 67 in the wall 61 of the casing to prevent relative rotation between the inner bolster and casing.

The interior of the bolster 70 decreases in diameter from top to bottom as defined by the ledges or shoulders 68. The blade 57 is tapered from top to bottom and is provided adjacent its bottom with a shoulder 69.

Preferably tapering spaces 71, one between the casing 50 and the bolster 51, and another 72 between the inner bolster portion 54 and the outer bolster 51, are provided to receive oil or other lubricant to effect the cushioning previously described, under the conditions specified. The lubricant is fed through passage 73 to the spaces 71 and 72, and the openings for passage of the lubricant may vary in number and relative location.

The construction of Fig. 4 accomplishes the same results as to absorption of vibrations as the embodiments of the invention above described, as it avoids the hammering effect of the blade both within the bobbins and within the mountings. This is due principally to the loose fit of the blade within the inner bolster, the loose fit of the inner bolster within the outer bolster, and the loose fit of the outer bolster within the casing, with due provision for cushioning by the oil films according to the varying conditions created during the spinning operation, and radial outward flow through the respective passages 47 and 48 to the respective spaces between the inner and outer bolster and outer bolster and bolster case for the same continuous cycle of recirculation as previously pointed out for the other embodiments.

Fig. 5 shows a further modification of the invention, and generally similar to the construction of Figs. 3 and 4. In Fig. 5, the inner bolster terminates adjacent the plane of the supporting rail and the outer bolster extends thereabove and is provided with an enlarged head chambered to

receive a roller bearing. The numeral 50' designates the casing or fixed support for the movable parts of the spindle. The casing 50' is provided with an extension 75 having a passage 76 through which the lubricant is supplied. This is standard structure and may be used in connection with any of the embodiments hereinbefore described. A hinged cap 77 closes the inlet end of the passage 76. A lever or knee brake 78, of known construction and operation, is provided to clamp the whirl and stop rotation of the spindle when desired.

The outer bolster 79 is provided on its lower end with a seat 80 for the inner bolster 81. The inner bolster has secured within its lower end as by a pin 82, a plug which serves as a bearing surface for the end 84 of the blade 85, similar in construction to the blade 57 of Fig. 4. It will also be noted without further detailed description that the interior of the inner bolster 81 is formed to accommodate the stepped or tapered construction of the blade 85.

As previously mentioned, in connection with the construction of Fig. 5, the upper end of the bolster 79 is provided with an enlarged chambered head which is designated by the numeral 86, and the inner bolster 87 is provided with an annular flange 88 which fits within the chamber 89 of the head 86. The flange or head 88 is provided with an opening or openings 90 to permit the circulation of oil in accordance with the principles of the invention relating to method of lubrication. The head 88 of the inner bolster is keyed to the enlarged head 86 of the outer bolster 79 as by means of a pin 91 to prevent relative rotation therebetween. The outer bolster is maintained against rotation relative to the casing 50' as by means of a key 92 which engages in a longitudinal groove 93 in the wall 94 on the upper end of the casing support. The blade 85 may be rotated in known manner by a whirl 95, and the antifriction bearing 96 may be provided for the purposes described in the aforesaid prior patent and for cooperation with the other features above described and pointed out for properly maintaining the axis of rotation of the blade and bobbin thereon in true vertical alignment within such close limitations as will prevent hammering and gyratory or oscillating movements between the bearing and the load, which oscillations or vibration when not absorbed normally result in destruction of the blade, the bolsters or bobbin. When proper balance is maintained, in the manner specified, the blades, the bolsters and bobbins will not hammer in any marked degree even when large bobbins are carried on the blades. It is obvious that in this embodiment also the continuous circulation of oil will take place in the manner hitherto described.

It should be noted from the foregoing that the possible variation, combinations, and permutations, in the present invention to accomplish the attainment of the stated objects and advantages, are practically unlimited as to details. For instance in Fig. 2, two loosely mounted inner and outer bolsters are supported on the bottom of the casing, and the step of the inner bolster supports the blade at its bottom end to carry the load. In Fig. 3 both inner and outer bolsters extend substantially to the top of the casing with the bolsters shouldered adjacent the top of the casing, and the blade mounted within the inner bolster. In Fig. 4 the outer bolster terminates below the upper end or chamber of the inner bolster, which chamber supports the ball bear-

ing; whereas in Fig. 5 the construction of Fig. 4 is reversed so that the outer bolster extends above the inner bolster and is provided with a chambered head supporting a self-aligning ball bearing. Thus the fulcrums for oscillating movements of the bolsters and blades may be varied.

It is obvious that if desired, as shown in said prior Patent #1,511,257, the plug 15 may be removed to permit the continuous circulation of oil first axially downwardly through the lower end of the hole 15a and that the spindle may be constructed below the step in the manner shown in said patent to permit the oil to then circulate 10 radially outwardly to be fed upwardly as said respective cushioning oil films in the spaces between the inner and outer bolsters and outer bolster and case in the manner previously explained. We have shown such a construction in Figs. 6-9 which is similar to the construction shown in Fig. 2 herein, modified in accordance with the teachings of said prior Beede Patent No. 1,511,257, with the plug 15' thereof removed to 15 permit the continuous circulation of oil, first axially downwardly through the lower end of the hole 15a as indicated by the arrows U and then radially outwardly as indicated by V underneath the innermost bolster 18' to be fed upwardly at modulated speed as indicated by the oil film and 20 arrows W between the innermost bolster 18' and outer bolster 9'. We have shown in Figs. 6-9 the embodiment of means for non-rotatably securing the lower end of a spindle bolster, such as the outer bolster 9' to the lower end of its bolster casing shown in the copending application of 25 Herbert G. Beede, one of the joint members herein, S. N. 209,470, Means for non-rotatably securing the lower end of a spindle bolster to the lower end of its bolster case, filed May 23, 1938, in 30 which the fingers 100 project upwardly from the base plug 102 into a plurality of complementary slots 104 in the lower end of the outer bolster 18' of greater length than said fingers 102 to provide the radial oil circulation openings 106 in the 35 lower end of said bolster means 18' between the ends of said fingers 100 and slots 104. It is thus 40 obvious that a portion of the oil stream fed upwardly as at W will be circulated radially outwardly through said holes 106 to be fed radially upwardly as indicated by the films and the arrows X between the outermost bolster 18' and bolster case 7'. It will be noted that the respective outermost bolster 9' is spaced so closely from 45 its inner bolster 18' and bolster case 7' respectively with the clearances mentioned above 50 throughout the height thereof as to permit continuous films of lubricant as indicated by the respective arrows W and X to be urged upwardly by the capillary action of the lubricant between said 55 respective bolsters 9' and 18' and outer bolster 9' and bolster case 7' as continuous films to be 60 forced to ooze inwardly on rotation of the spindle blade over the upper ends of the respective bolster means, as indicated by the arrows Y over the upper end of the outer bolster means 9' and 65 by the arrows Z over the upper end of the innermost bolster means 18' by rotation of the spindle blade to flow downwardly as indicated by the arrows T over the bearing 10' to lubricate said 70 respective bearings 10' and 15' and spindle blade 11'. It is apparent, however, that if either bolster means be only so closely spaced with the proper clearance from the other bolster means or the bolster case for a substantial distance adja- 75 cent the upper end thereof, that a modulated

flow will still be produced between the upper ends of said members even if a churning action takes place between the lower portions of the respective members spaced apart a greater distance than said respective clearance distance.

While our invention is especially adapted for use on spindles adapted to carry bobbins for spinning or twisting yarn or thread, it is apparent that it may be employed on any type of a rotatable spindle for any other use such as in extractors.

In all embodiments of the invention the result is substantially the same as to accomplishment of the objects of the invention hereinafter stated, and we have shown the several embodiments in this application purely as illustrative and representing preferred forms at the present time.

What we claim is:

1. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing fixed in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

2. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means, a separate upper bearing comprising an anti-friction bearing forming a center of oscillation between the upper end of such upwardly extending bolster means and said spindle blade to take up the radial thrust of said spindle blade and a bearing in the lower end of the innermost

bolster means having a vertical hole substantially centrally thereof for loosely containing the lower end of said blade, said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

3. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

4. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing fixed in the lower end of said innermost bolster means having a vertical hole substantially centrally thereof for loosely containing the lower

end of said blade, said bolster means having passage means from said lower bearing hole for the radial circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing to the lower end of said spindle blade for successive continuous cycles of recirculation.

5. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending toward the top of said bolster case in closely spaced relationship thereto throughout the height of such bolster means and provided with an upper bearing near the upper end thereof to take the radial thrust of said spindle blade and a bearing fixed in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

6. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade and means for maintaining said bolster means against rotation relative to said case and to each other,

said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

7. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation, said higher bolster means being so closely spaced from the bolster case for a substantial distance adjacent the upper end thereof as to permit a continuous film of lubricant to be urged upwards by the capillary action of the lubricant between said higher bolster means and the bolster case to form a continuous radial cushion for said upper bearing and to be forced to continuously ooze inwardly over the upper end of said bolster means by the rotation of said spindle blade and then flow downwardly to lubricate said bearing and spindle blade, each of the inner bolster means being variably spaceable from said outermost bolster means in sufficient amounts to provide lubricant cushions of sufficient area to absorb the oscillatory and high speed vibrations of said spindle blade.

8. A spindle, comprising, in combination, a bolster case, a spindle blade extending substantially vertically and substantially centrally of said bolster case, a plurality of bolster means contained in nested closely spaced relationship within said bolster case and adapted to be rela-

tively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means, a separate upper bearing comprising an anti-friction bearing forming a center of oscillation between the upper end of such upwardly extending bolster means and said spindle blade to take up the radial thrust of said spindle blade and a bearing in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation, said higher bolster means being so closely spaced from the bolster case for a substantial distance adjacent the upper end thereof as to permit a continuous film of lubricant to be urged upwards by the capillary action of the lubricant between said higher bolster means and the bolster case to form a continuous radial cushion for said upper bearing and to be forced to continuously ooze inwardly over the upper end of said bolster means by the rotation of said spindle blade and then flow downwardly to lubricate said bearing and spindle blade, each of the inner bolster means being variably spaceable from said outermost bolster means in sufficient amounts to provide lubricant cushions of sufficient area to absorb the oscillatory and high speed vibrations of said spindle blade.

9. A spindle, comprising, in combination, a bolster case, a spindle blade extending substantially vertically and substantially centrally of said bolster case, a plurality of bolster means contained in nested closely spaced relationship within said bolster case, and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing fixed in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly at a modu-

lated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation, said higher bolster means being so closely spaced from the bolster case for a substantial distance adjacent the upper end thereof as to permit a continuous film of lubricant to be urged upwards by the capillary action of the lubricant between said higher bolster means and the bolster case to form a continuous radial cushion for said upper bearing and to be forced to continuously ooze inwardly over the upper end of said bolster means by the rotation of said spindle blade, and then flow downwardly to lubricate said bearing and spindle blade, each of the inner bolster means being variably spaceable from said outermost bolster means in sufficient amounts to provide lubricant cushions of sufficient area to absorb the oscillatory and high speed vibrations of said spindle blade.

10. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade and means for maintaining said bolster means against rotation relative to said case and to each other, said bolster means having passage means from said lower bearing hole for the radial circulation of lubricant radially outwardly therethrough to be urged upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation, said higher bolster means being so closely spaced from the bolster case for a substantial distance adjacent the upper end thereof as to permit a continuous film of lubricant to be urged upwards by the capillary action of the lubricant between said higher bolster means and the bolster case to form a continuous radial cushion for said upper bearing and to be forced to continuously ooze inwardly over the upper end of said bolster means by the

rotation of said spindle blade, and then flow downwardly to lubricate said bearing and spindle blade, each of the inner bolster means being variably spaceable from said outermost bolster means in sufficient amounts to provide lubricant cushions of sufficient area to absorb the oscillatory and high speed vibrations of said spindle blade.

11. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means, a separate upper bearing comprising an anti-friction bearing forming a center of oscillation between the upper end of such upwardly extending bolster means and said spindle blade to take up the radial thrust of said spindle blade and a bearing in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

12. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade and means for maintaining said bolster means against rotation relative to said case and to each other, said bolster means having passage means from said lower bearing hole for the radial circulation of lubricant radially outwardly therethrough to be urged upwardly between said bolster means and said outermost bolster means and bolster case on rotation of the spindle blade to provide

therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation.

13. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation, said bolster means being so closely spaced from each other and the outermost bolster means being so closely spaced from the bolster case throughout the height thereof as to permit continuous films of lubricant to be urged upwardly by the capillary action of the lubricant and to be forced to continuously ooze inwardly by the rotation of the spindle blade over the upper ends of the respective bolster means and then flow downwardly to said lower bearing hole to lubricate said bearings and spindle blade.

14. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing fixed in the lower end of said spindle blade having a vertical hole substantially centrally thereof

for loosely containing the lower end of said blade, said bolster means having passage means from said lower bearing hole for the radial circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing to the lower end of said spindle blade for successive continuous cycles of recirculation, said bolster means being so closely spaced from each other and the outermost bolster means being so closely spaced from the bolster case throughout the height thereof as to permit continuous films of lubricant to be urged upwardly by the capillary action of the lubricant and to be forced to continuously ooze inwardly by the rotation of the spindle blade over the upper ends of the respective bolster means and then flow downwardly to said lower bearing hole to lubricate said bearings and spindle blade.

15. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means, a separate upper bearing comprising an anti-friction bearing forming a center of oscillation between the upper end of such upwardly extending bolster means and said spindle blade to take up the radial thrust of said spindle blade and a bearing in the lower end of the innermost bolster means having a vertical hole substantially centrally thereof for loosely containing the lower end of said blade, said bolster means having passage means from said lower bearing hole for the radial circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles of recirculation, said bolster means being so closely spaced from each other and the outermost bolster means being so closely spaced from the bolster case throughout the height thereof as to permit continuous films of lubricant to be urged upwardly by the capillary action of the lubricant and to be forced to continuously ooze inwardly by the rotation of the spindle blade over the upper ends of the respective bolster means and then flow downwardly to said lower bearing hole to lubricate said bearings and spindle blade.

16. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade and means for maintaining said bolster means against rotation relative to said case and to each other, said bolster means having passage means from said lower bearing hole for the radial circulation of lubricant radially outwardly therethrough to be urged upwardly between said bolster means and bolster case to be discharged radially inwardly over the upper end of said upwardly extending bolster means and downwardly over said upper bearing and within said lower bearing hole for successive continuous cycles of recirculation, said bolster means being so closely spaced from each other and the outermost bolster means being so closely spaced from the bolster case throughout the height thereof as to permit continuous films of lubricant to be urged upwardly by the capillary action of the lubricant and to be forced to continuously ooze inwardly by the rotation of the spindle blade over the upper ends of the respective bolster means and then flow downwardly to said lower bearing hole to lubricate said bearings and spindle blade.

17. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally one within the other relative to said bolster case, spindle blade and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof for loosely containing the lower end of said blade, said bolster having passages from said lower bearing hole for the radial circulation of lubricant radially outwardly therethrough to be urged

upwardly at a modulated speed between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing and within said lower bearing hole for successive continuous cycles for recirculation.

18. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally relative to said bolster case and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing in the lower end of the innermost bolster means having a vertical hole substantially centrally thereof providing a bearing for the lower end of said blade, said bolster means having passage means for the circulation of lubricant radially outwardly therethrough to be urged upwardly between said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly ex-

tending bolster means and downwardly over said upper bearing and within said lower bearing hole for successive continuous cycles of recirculation.

19. A spindle, comprising, in combination, a bolster case, a spindle blade extending substantially vertically and substantially centrally of said bolster case, a plurality of bolster means contained in nested closely spaced relationship within said bolster case and adapted to be relatively movable laterally relative to said bolster case and to each other on rotation of said spindle blade in use, all of said bolster means extending upwardly a substantial distance within said bolster case from substantially the lower end thereof and one of said bolster means extending towards the top of said bolster case in closely spaced relationship thereto throughout the height of such bolster means and provided with an upper bearing near the upper end thereof to take up the radial thrust of said spindle blade and a bearing fixed in the lower end of said innermost bolster means having a vertical hole substantially centrally thereof for containing the lower end of said blade, said bolster means having passage means from the lower portion of said innermost bolster means outwardly through said bolster means for the circulation of lubricant radially outwardly therethrough to be urged upwardly between said bolster means and said outermost bolster means and bolster case on rotation of the spindle blade to provide therein continuous cushioning bodies of lubricant for dampening different sets of vibrations and a continuous circulation of lubricant upwardly between said bolster means and bolster case to be discharged radially inwardly over the upper end of said upwardly extending bolster means and downwardly over said upper bearing to the lower end of said spindle blade for successive continuous cycles of recirculation.
